FIG. 1.

FIG. 2.

FIG. 3.

FIG. 4.

FIGURE 1 is a perspective view of a vertically arranged, rotatable extruder showing my new design;

FIGURE 2 is a perspective view of the rotatable extruder shown in FIGURE 1 as viewed substantially from the left side thereof;

FIGURE 3 is a perspective view of the rotatable extruder shown in FIGURE 1 as viewed substantially from the rear thereof; and

FIGURE 4 is a perspective view of the rotatable extruder shown in FIGURE 1 as viewed substantially from the right side thereof.

This application is a continuation-in-part of my earlier-filed application, Serial Number D. 63,889, filed February 10, 1961, now abandoned.

I claim:

The ornamental design for a rotatable extruder, substantially as shown and described.
